UNITED STATES PATENT OFFICE.

FRANK E. STEBBINS, OF WASHINGTON, DISTRICT OF COLUMBIA.

ALCOVE SLEEPING-CAR.

No. 897,797.

Specification of Letters Patent.

Patented Sept. 1, 1908.

Original application filed December 24, 1897, Serial No. 663,352. Divided and this application filed December 11, 1905. Serial No. 291,322.

To all whom it may concern:

Be it known that I, FRANK E. STEBBINS, a citizen of the United States, residing at Washington, in the District of Columbia, 5 have invented certain new and useful Improvements in Alcove Sleeping-Cars, of which the following is a specification sufficiently full, clear, and accurate as will enable those skilled in the art to embody and use 10 the same.

The improvements relate to alcove sleeping cars and embrace certain matters disclosed in my prior application filed December 24, 1897, No. 663,352, of which application 15 the present application is in part a continuation and division.

The object of my invention is, generically, the reorganization and improvement of the ordinary sleeping car interior construction 20 and arrangement as a whole, and specifically the provision at each side wall of a sleeping car having a central passage way, and in connection with each so called section, or each two sections, of an alcove within which the 25 occupants of a section adjacent an alcove, or the occupants of the sections each side of the alcove, may disrobe at night and dress and wash in the morning, said alcove to be entirely shut off from the section, or from the 30 sections adjacent thereto on each side thereof, by partitions entirely or partly movable or removable in such a manner that access to both the upper and lower berths when adapted for use shall be possible only from 35 the central passage way of the car.

A further object is the provision of pivoted upper berths which may be contracted, or their widths narrowed, so they can be turned about their pivots and occupy the limited 40 space available in positions substantially parallel with the side wall of the car, thus securing a wide open space in the top portion of the car between the seat backs and the ceiling or roof.

45 A further object is the provision of movable or removable means for inclosing a portion of each alcove and forming a receptacle for storing all or part of the bedding by day, and also providing a space above each receptacle and between the seat backs for the reception of hand baggage, etc.

50 Further objects relate to inclosing the upper portions of the alcoves between the bulkheads and the wall of the car, the strengthening of the car, the formation of the upper

berths, the folding wash basin, and other details of construction whereby the car is better adapted for use as a sleeping car and at the same time its general appearance improved when arranged for use by day.

With these main ends in view the invention consists in certain novelties of construction, arrangements, combinations and organization of parts as herewith set forth and claimed.

The accompanying drawings illustrate the physical embodiment of the invention or inventions, constructed according to the best modes I have so far devised for the practical applications of the principles.

Figure 1 is a plan view of a car provided with a series of sections and alcoves each side of a central passageway, toilet rooms at the ends of the car, and with swinging doors or fixed partitions between the toilet rooms 75 and the central portion of the car. Fig. 2 shows another plan of a car embodying the improvements and wherein modified arrangements are introduced at the ends. Fig. 3 is a cross section of Fig. 1 between two pairs of 80 seats and on the line *a—a*, the upper berths being in section, one of which is shown contracted and folded up against the wall, and the other lowered and extended for use. Fig. 4 is a cross section of Fig. 1 through two 85 alcoves and on line *b—b*, one of the alcoves being open and with the wash basin let down for use, and the other one closed and arranged as it appears by day. Fig. 5 is a fragmentary view in elevation of one side 90 of the car, the section being taken on line *c—c* of Fig. 1, the upper berth at the left being lowered and extended for use, and the alcove and upper berth at the right both being closed up. Fig. 6 is a perspective view of 95 a part of one side of a car having a series of alcoves between seat backs and upper berths which close up to the clear story sill, the extreme end section being partly arranged for sleeping purposes.

100 Referring to the several figures, the numeral 1 designates the floor of the car; 2, the side walls which are provided with windows as shown in the several figures, or otherwise arranged as may be desired; 3, the plates; 105 4, the roof above the plates; 5, the clear story, of any desired construction; 6, the clear story sills; 7, the series of arch rails which unite the clear story sills and strengthen the top of the car, said arch rails being lo-

cated substantially in line with the series of seat back boards, though they may be in planes slightly to one side of each of said backboards; 8, the central passage way of the car; 9, the seat backs or partitions made of any suitable material, either wood or metal, each seat back or partitions being approximately 42" in height from the floor and fixed in position with one edge abutting the wall and the seat back or partition itself at right angles to the wall; 10, the fixed bulk head boards or partitions each preferably in line with a seat back board and with one edge abutting the wall, said boards extending to the plate or roof, and each being of sufficient area to cover one end of an upper berth when closed up or folded; 11, the fixed pairs of seats, the seats of each pair facing each other, as shown, and each seat comprising an end board 12, a cushion rail 13, a movable upholstered cushion 14, a removable upholstered back piece 15, an arm rest 16, a support for the rear edge of a cushion, and the back board which supports the head rest, the cushions 14 and pieces 15 of both seats being adapted to be moved into position and to form a horizontal lower berth foundation in a well known or any other manner; 16', the upper berth in line with the pairs of seats and directly above the same, each upper berth when contracted and closed being located between the bulk head boards; 17, the pivotal hinges at each end of a berth by which the inner portions of the said upper berths are secured to the bulk heads or car wall and in a horizontal line adjacent the upper edges of the main windows; 18, torsion braided wire mattresses or bed bottoms; 19, the chains or cords each of which at one end is secured to the upper berth and at the other end preferably to a fusee 20 located in an alcove and upon a bulkhead, an opening being provided for the passage of the chain (see Fig. 3); 21, an anti-friction wheel located at the opening and preferably in the alcove and over which the chain or rope travels; 22, the berth panel having the inner edge curved and extended so that when the berth is in a horizontal position the body of the panel and mattress will lie in a lower plane than a parallel plane passed through the pivots (see Fig. 5 at the left and Fig. 3 at the right); 23, the end strengthening pieces secured at right angles to the panel and which pieces preferably carry the pivots or journals of the hinges; 24, the hinged front edge of the upper berth, in Figs. 3 and 5 shown in this instance made of wood and folding over onto the main portion; 25, the hinges; 26, spring actuated bolts or catches which engage and hold the berth in closed position against the wall; 27, the rotary shaft which operates rods to retract the spring bolts at each end of the berths in a well known manner; 28, hooks secured to the arch rail; 29, a curtain rod secured

in the arch rails, as shown; 30, wire cords, chains, or straps, each secured at one end to the outer edge of a berth and the other end provided with a loop or ring to pass over a hook 28, as shown, these chains or cords supporting the outer edge of the berth in whole or in part; 31, a berth guard of canvas, of less length than the length of the berth so as to leave an opening to the upper berth, with one edge attached to the front edge of the berth and the top edge thereof held by a cord which in turn is secured at its ends to the ropes 30, as shown; and 32 is a panel apron or finishing strip which matches the edge of the berth panel when closed so as to present a continuous surface.

In Figs. 3 and 5 the front part of the upper berth is hinged so as to fold over upon the main portion thus contracting and diminishing the width so the berth may fold to a position parallel with the wall and between the bulk heads. The mattress being flexible or divided on the line of the hinges 25 also can fold upon itself, as shown at the left in Fig. 3.

The number 36 designates removable hinged folding head boards or partitions which rest upon the top edges of the seat back boards and match the edges of the bulk heads so as to entirely shut off an alcove from the pairs of seats—beadings and fastenings or locks of any desired kind being employed to hold the said partitions in place; 37 are the series of alcoves adjacent the pairs of seats, each alcove being bounded by the floor of the car, two fixed seat back boards, two bulkhead boards, the car roof, and the car wall by day, and by the two head boards in addition thereto by night; 54, the areas of the floor spaces identified as sections; 38, posts with their lower ends located within the alcoves and adjacent the ends of the seat back boards, and with their upper ends secured to the arch rails; 39, closets or pockets preferably in the walls of the car; 40, the hinged doors for the pockets, each being provided with a mirror; 41, the hinged folding supports or boxes for the wash basins, each support being substantially the width of the alcove so as to catch any water which may be scattered in washing, and prevent the same from falling to the floor; 42, the basins secured within the supports; 43, faucets; 44, water delivery pipes; 45, waste water pipes discharging through the floor; 46, hinged movable or removable end boards for closing the lower parts of the alcoves adjacent the central passageway; 47, seats for the edges of the same in the posts which latter are slightly cut away; 48, the hinged top covers located below the tops of the seat backs some distance so as to provide a space between the seat backs for hand baggage, etc.; 49, a cross cleat to support the inner edge of the cover; 50, cleats on the under surface of the cover to hold it in place and prevent endwise movement; 51 designates openings under the seat

back boards to the space beneath the seat cushions, whereby the capacity of the receptacle is increased; 52, are spring roller curtains or flexible blinds; and 53 grooves in the 5 bulk head boards for guiding the edges of the curtains, which latter when pulled down by day close the otherwise open spaces between the upper berths when folded and form a continuous and uniform surface thus improving 10 the appearance of the car interior above the windows.

In Figs. 1 and 2 the toilet rooms 56 are located at the corners of the car each side of the door way, and in Fig. 1 swinging doors or 15 partitions 57 are placed so as to hide the said toilet rooms from the central passage way and central part of the car. The doors where used are locked when the car is in transit so the passenger must travel around 20 the post or edge 58 to reach the toilet rooms. Permanent partitions, however, may be employed as screens in place of the doors. One of these doors or partitions is clearly shown in elevation at the right in Fig. 6.

25 A permanent head board or partition 59 may be used above the seat back, at the right in Figs. 1 and 6, or the same may be movable as indicated at 59 at the left in Fig. 1, where the head board or partition is in 30 place upon the seat back. See also Fig. 2 at the right. The seat backs at opposite ends of the car in Fig. 1 and also at the left in Fig. 2 are provided with fixed head boards or partitions 60, or the seat back and partition 35 may be integral.

The plan arrangement of Fig. 1, where the two alcoves are located at the extreme ends of the body of the car upon opposite sides of the central passage way and adjacent the 40 permanent partitions 61 each of which bounds one of the toilet rooms, and partitions or doors 57, is advantageous inasmuch as it allows the car body to be made some two feet shorter than otherwise would be possible.

45 In Fig. 6 there is shown an alcove sleeping car interior arrangement with hinged upper berths which do not contract and which close up so that the outer edge of the berth engages the clear story sill. The posts and arch rails present in the first example are here omitted though they may be used, and the alcoves are shown open. Folding or permanent wash basins and other paraphernalia for 50 toilet purposes are present. The section at the extreme right is partly arranged for night use, the upper berth being lowered and the seat cushions and back upholsterings moved to form a lower berth foundation, and the alcove at the left entirely shut off from the adjacent pairs of seats, and upper berths when lowered, by the removable and hinged folding head boards. The alcove for use by the 55 occupants of the partly arranged section is at the right of the section, and inclosed except

at the front, as shown. The head boards are made permanent, or fixed partitions employed, when a car of this type is to be designed for a state room or compartment car. In practice a curtain, of course, is used to 70 shut off each section and an adjacent alcove from the central passage way, said curtain being suspended from the rod above the alcove and the hooks on the arch rails. A supplemental curtain may be used for screening the lower berth.

When fewer alcoves are present in the body of the car, that is, where one alcove is interposed between each two sections or pairs of seats and upper berths and is to be used by the occupants of two adjacent lower and two adjacent upper berths for undressing, washing and dressing, the same may be made wider than shown, and two folding or permanent wash basins be provided, or the 80 alcove may be of a double construction with a removable curtain or partition between the two, thus forming two alcoves side by side.

85 From the foregoing description of the car interior reorganizations and arrangements, 90 taken in connection with the drawings, it becomes apparent that important new and very desirable results are secured. The interior of the car in the main view is but little obstructed in the top above the horizontal 95 plane of the seat backs inasmuch as the upper berths contract or fold and occupy perpendicular positions against the side walls and do not project more than 10" or 12" from the car side; the alcoves are open only 100 to the passage way at night and each is provided with toilet appliances whereby the passenger half dressed is not obliged to travel the length of the car in the morning to reach the wash rooms, as is necessary in the sleeping car now in common use; and arch rails and posts are provided in the preferred construction to strengthen the car.

105 It will be observed that the alcoves are open and practically unobstructed when arranged to be used by passengers for undressing, dressing and washing, and that the floor of an alcove is on a level with the floor of the car, though a supplemental floor may be used located several inches above the main floor 110 to allow the introduction of steam heating or water pipes, or both, beneath the same, and that a portion of the alcove may be inclosed to form a receptacle for the removable bedding and head boards by day. This provision of convenient receptacles for the removable bedding by day is of great importance, as otherwise the same would necessarily be stored between the upper berths and the car wall, in which case contracting berths 115 closed to perpendicular positions against the car sides could not practically be employed.

120 Each berth is isolated from every other berth and from the alcoves at the ends so that each alcove affords an entirely secluded area.

inclosed by rigid partitions and walls upon all sides, except the front which is screened by a curtain, where the acts of dressing at night and dressing and washing in the morning may be performed in privacy.

To properly estimate the importance of the results secured by the reorganization of the car interior construction and arrangements, as herewith set forth, the reorganization should be viewed as a whole or a totality, wherein there is a reciprocal adaptation of the several parts and elements to attain the general result and the specific ends.

It is obvious that in the practical embodiment of the improvements parts may be substituted for those shown and modifications introduced which will not constitute substantial departures. For instance, permanent wash basins may be located within the alcoves in lieu of those which fold; different movable or removable partitions be employed to inclose part of an alcove so as to form a receptacle for bedding; means substituted for performing the functions of the removable or movable head boards, that is, to shut off the alcove from the upper and lower berths by night, so access to the same can be had only from the central passage way; and analogous changes introduced.

30. What I claim is:

1. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; and means for forming lower and upper berths located entirely within the sections.

2. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; means for forming lower and upper berths in the sections; and toilet appliances, embracing wash basins, located in the alcoves.

3. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; means for forming

upper and lower berths in the sections; and movable means for inclosing parts of the alcove spaces to form receptacles therein for bedding by day.

4. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; means for forming upper and lower berths in the sections; and movable end and top cover boards or partitions for inclosing parts of the alcove spaces to form receptacles and spaces above the top covers for hand baggage.

5. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; means for forming lower berths in the sections; hinged and folding upper berths in the sections; and toilet appliances in the alcoves.

6. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; means for forming lower berths in the sections; contracting upper berths in the sections which can be folded to substantially vertical positions; and movable means for inclosing a part of each alcove space to form a receptacle.

7. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; seats in the sections the upholsterings of which can be adjusted to form lower berths; upper berths in the sections the main parts of which can be folded to substantially vertical positions; and toilet appliances in the alcoves.

8. The combination in a sleeping car and with the floor and walls, of fixed rigid seat backs or partitions located adjacent the walls

and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; means for forming upper and lower berths in the sections; and folding wash-basins located in the alcoves and adjacent the walls.

10. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; means for forming upper and lower berths in the sections; wash basins in the alcoves located adjacent the walls; and openable pockets or closets above the basins.

15. 10. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; two seats in each 20 section facing each other the upholsterings of which are movable to form a lower berth; means for forming an upper berth in each section; toilet appliances in the alcoves; and movable means for inclosing part of each 25 alcove below the tops of the seat backs.

20. 11. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections 30 from the alcoves by night; toilet appliances located in the alcoves; seat upholsterings which can be transformed into a lower berth in each section; and an upper berth in each section; the alcove spaces being free and un- 35 obstructed for use by passengers in undressing, dressing and washing.

25. 12. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections

from the alcoves by night, an alcove being located at the end of each section for use by the occupants of the section; and means for forming lower and upper berths in the sections.

70

13. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night, an alcove being located at the end of each section; means for forming upper and lower berths in the sections; and toilet appliances in the alcoves.

75

14. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night, an alcove being located at the end of each section; means for forming lower and upper berths in the sections; and movable means for inclosing part of each alcove space to form a receptacle.

80

15. The combination in a sleeping car and with the floor and walls, of fixed rigid seat backs or partitions located adjacent the walls and substantially at right angles thereto dividing the floor area into a central passage way, sections, and alcoves adjacent the walls; movable partitions adjustable in connection with the fixed seat backs or partitions and entirely shutting off the ends of the sections from the alcoves by night; means for forming lower and upper berths in the sections; and toilet appliances in the alcoves; the alcoves being free and unobstructed with their floors substantially on a level with the floor of the central passage way.

95

16. The combination in a sleeping car and with the floor and walls, of fixed vertical seat backs 9 dividing the floor area adjacent the wall into a section 54 and an alcove 37, partitions in connection with the seat backs one of which is movable and entirely shuts off the section from the alcove, said alcove being closed at both sides and open at the front only; seats in the section the upholstering of which can form a lower berth; an upper berth; and movable means for inclosing part of the alcove to form a receptacle.

105

17. The combination in a sleeping car and with the floor and walls, of fixed seat backs or partitions located adjacent the walls and substantially at right angles thereto dividing the floor area into a central passage way, sections, and alcoves adjacent the walls, said

110

115

120

125

130

6 alcoves being free and unobstructed; bulk-heads above the seat backs; movable partitions adjustable in connection with the seat backs or partitions and bulk-heads and 10 adapted to entirely shut off the ends of the sections from the alcoves by night; seat and back upholsterings in each section for forming a lower berth; and an upper berth in each section hinged to the car and adapted to be 15 folded to a position between the bulk-heads.

18. The combination in a sleeping car and with the floor and walls, of fixed seat backs or partitions located adjacent the walls and substantially at right angles thereto dividing 15 the floor area into a central passage way, sections, and alcoves adjacent the walls; bulk-heads above the seat backs; posts extending from the seat backs to the roof or arch rails; movable partitions adjustable in connection 20 with the seat backs, bulk-heads and posts and adapted to entirely shut off the ends of the sections from the alcoves; and lower and upper berths in the sections.

19. The combination in a sleeping car and 25 with the floor and walls, of vertical seat backs located adjacent the car walls and at right angles thereto dividing the floor area into a central passage way, sections, and alcoves; bulk-heads in line with the seat backs; seats 30 and upholsterings adapted to be adjusted to form a lower berth, and a hinged upper berth in each section; movable means for inclosing part of each alcove; and movable head boards in connection with the seat backs and 35 bulk-heads for entirely shutting off the alcoves from the sections; said upper berths being so constructed that they can be contracted or made narrower than when adapted for use and turn up to vertical positions ad- 40 jacent the car walls and between the bulk-heads.

20. The combination in a sleeping car and with the floor and walls, of fixed seat backs or partitions located adjacent the walls and sub- 45 stantially at right angles thereto dividing the floor area into a central passage way, sections, and alcoves adjacent the walls; posts extending between the seat backs and the roof or arch rails; and movable partitions in 50 connection with the seat backs and posts for entirely shutting off the ends of the sections from the alcoves.

21. The combination in a sleeping car and with the floor and walls, of fixed seat backs or 55 partitions located adjacent the walls and sub- stantially at right angles thereto dividing the floor area into a central passage way, sections, and alcoves adjacent the walls; bulk-heads above the seat backs; movable parti- 60 tions in connection with the seat backs and bulk-heads for entirely shutting off the ends of the sections from the alcoves; means for forming lower berths in the sections; hinged upper berths in the sections which can be 65 turned to vertical positions adjacent the

walls and between the bulk-heads; and movable means for inclosing part of each alcove space to form a receptacle by day; each alcove affording a free and unobstructed space for the passenger in undressing and dressing. 70

22. The combination in a car having a central passage way, of seats with fixed backs arranged in pairs each side of the passage way, the seats of each pair facing each other; removable seat cushions and upholstered 75 back pieces adapted to be shifted and form a lower berth foundation between the backs of each pair of seats; a pivoted upper berth located directly above each pair of seats and in line therewith; bulk heads substantially in 80 line with the seat backs and between which the upper berth can close; alcoves between adjacent pairs of seats and upper berths, each affording an unobstructed space for a passenger while undressing and dressing; and removable head boards or partitions in connection 85 with the seat backs and bulkheads.

23. The combination in a car having a central passage way, of seats with fixed backs arranged in pairs each side of the passage 90 way, the seats of each pair facing each other; removable seat cushions and upholstered back pieces adapted to be shifted and form a lower berth foundation between the backs of each pair of seats; a pivoted upper berth 95 located directly above each pair of seats and in line therewith; bulk heads substantially in line with the seat backs and between which the upper berth can close; alcoves between adjacent pairs of seats and upper berths, each 100 affording an unobstructed space for a passenger while undressing and dressing; and removable head boards or partitions matching the top edges of the seat backs and bulkheads. 105

24. The combination in a car having a central passage way, of seats with fixed backs arranged in pairs each side of the passage way, the seats of each pair facing each other; removable seat cushions and upholstered 110 back pieces adapted to be shifted to form a lower berth foundation between the backs of each pair of seats; a pivoted upper berth located directly above each pair of seats and in line therewith; bulk heads substantially in 115 line with the seat backs and between which the upper berth can close; alcoves between adjacent pairs of seats and upper berths, each alcove being unobstructed and provided with a folding wash basin located adjacent the car wall, whereby a free space substantially at the floor level is provided for a passenger while undressing, dressing, and washing. 120

25. The combination in a car having a central passage way, of seats arranged in pairs each side of the passage way, the seats of each pair facing each other; removable seat cushions and upholstered back pieces adapted 125 to be shifted to form a lower berth founda- 130

tion; a pivoted upper berth located above each pair of seats and in line therewith; and alcoves between adjacent pairs of seats, said alcoves being free and unobstructed and entirely shut off at their sides from the pairs of seats by movable partitions, whereby access to the berths is possible only from the central passage way.

26. The combination in a car having a central passage way, of seats arranged in pairs on each side of the passage way, the seats of each pair facing each other; removable seat cushions and upholstered back pieces adapted to be shifted and form a lower berth foundation; a pivoted upper berth located above each pair of seats and in line therewith, said upper berth being adapted to fold to a vertical position against the wall; alcoves between adjacent pairs of seats, said alcoves being entirely shut off at their sides from the pairs of seats by movable rigid partitions, whereby access to the berths is possible only from the central passage way; and removable or shifting means for inclosing a part of each alcove to form a receptacle.

27. A railway car having an open central passage; sections disposed along each side of the car, each section comprising a pair of seats facing each other and convertible into a lower berth, and a pivoted upper berth in line with the seats; an alcove adjacent each section; and means for entirely inclosing each alcove except at the front so that access to the berths shall be possible only from the central passage way.

28. A railway car having an open central passage; sections disposed along each side of the car, each section comprising a pair of seats facing each other and convertible into a lower berth, means for forming an upper berth in a plane above the seats; an alcove adjacent each section; means for entirely inclosing each alcove except at the front so that access to the berths shall be possible only from the central passage way; and suitable removable or shifting means to inclose a part of an alcove to form a receptacle.

29. A railway car having an open central passage; sections disposed along each side of the car, each section comprising a pair of seats facing each other and convertible into a lower berth, and a pivoted upper berth in line with the seats; an alcove adjacent each section; and movable partitions for inclosing an alcove adjacent a section except at the front so that access to the berth shall be possible only from the central passage way.

30. A car having a floor and vertical walls, a series of sections adjacent the walls and forming a central passage way, each section comprising a pair of fixed back partitions and seats with upholsterings convertible into a lower berth, and a hinged upper berth above and in line with the pair of seats; bulk heads closing the ends of the upper berths when

folded; alcoves between the pairs of seats; and movable means for entirely closing an alcove except at the front and shutting it off from an adjacent section, said alcove being unobstructed so as to form a space substantially at the floor level for the passenger to stand while undressing and dressing.

31. A car having a floor; vertical walls; and series of sections adjacent the walls forming a central passage way, each section comprising two seats facing each other and a pivoted upper berth in line with the seats; fixed bulk heads closing the ends of the upper berths when folded; alcoves adjacent the sections each at the central portion of the car bounded by the car floor, wall, bulk heads, and seat backs; and movable partitions shutting off the sections from the alcoves, so that the latter are open only to the central passage way.

32. A car having a floor, vertical walls; and series of sections adjacent the walls forming a central passage way, each section comprising two seats facing each other and a hinged and vertically folding upper berth in line with the seats; fixed bulk heads closing the ends of the upper berths when folded; alcoves adjacent the sections bounded by the car floor, wall, bulk heads, seat backs, and partitions, part of the partitions being movable and adapted to shut off by night the sections from the alcoves, so that the latter shall be open only to the central passage way; removable or shifting means being provided to inclose part of the alcoves by day to form receptacles for bedding.

33. A car having a floor, vertical walls, and series of sections adjacent the walls forming a central passage way, each section comprising two seats facing each other and means for forming an upper berth in line with the seats; alcoves adjacent the sections each at the central portion of the car bounded by the car floor, wall, and seat backs; and movable partitions shutting off the sections from the alcoves, so that the latter are open only to the central passage way; each alcove being provided adjacent the wall with a folding wash basin.

34. A car having a floor, vertical wall, a section adjacent the wall, and an alcove adjacent the section; said section comprising a pair of seats the upholstering of which can be shifted to form a lower berth, and a hinged upper berth above the seats and in line therewith; means being provided to entirely inclose the alcove except at the front so that access to the berths is possible only at the fronts of the same.

35. A car having a floor, vertical wall, a section adjacent the wall, and an alcove adjacent the section; said section comprising a pair of seats the upholstering of which can be shifted to form a lower berth, and a hinged upper berth above the seats and in line there-

with removable means being provided to entirely inclose the alcove by night, except at the front, when the berths are arranged for use, so that access to the berths is possible only from the central passage way.

36. A car having along each side wall a series of sections and alcoves, a series of arch rails, and a series of posts extending from the seat backs, which bound the alcoves, to the 10 arch rails.

37. A car having along each side wall a series of sections and alcoves, a series of arch rails above the alcoves, and a series of posts extending between the arch rails and alcoves; 15 each alcove being provided with two posts located adjacent the seat backs.

38. A car having along each side a series of sections and alcoves, a series of arch rails, a series of posts extending between the alcoves and arch rails; and movable partitions 20 adapted to engage the posts and to be in part supported by the same.

39. The combination with a car, of a contracting upper berth comprising a panel of 25 the length of the berth hinged or pivoted at its rear edge adjacent the side of the car so as to swing through an arc of 90 degrees from a vertical to a horizontal position, and vice versa, a hinged extension for the outer edge 30 of the panel to increase the width of the berth outside the panel, and a mattress or bed bottom in connection with the panel and extension.

40. The combination with a car, of an upper berth comprising an inner part with a 35 panel of the length of the berth and pivoted at its rear edge to the car, and an outer part in connection with the inner part and adapted to be turned over the outer edge of the 40 panel and thus contract the width of the berth; said berth, when contracted and swung up, occupying a substantially vertical position adjacent the wall and roof of the car.

41. An upper berth for a sleeping car comprising a panel of the length of the berth pivoted to the car side, a front part connected to and which can be turned over or shifted onto the rear part, and a mattress or bed bottom in connection with both parts.

50 42. The combination with a car, of an upper berth comprising a panel with a curved inner edge pivoted adjacent the car side, and a front part hinged to the panel portion; the hinges being so disposed that the front part 55 can be turned over the edge of the panel and fold with it to a position in which the panel occupies a substantially vertical position adjacent the wall and roof.

43. The combination with a car, of an upper berth comprising a panel hinged at its inner edge to the car wall, and a front part pivoted to the panel portion to increase the width of the berth and which can be shifted or turned over parallel with the panel so the 65 latter can fold to a substantially vertical po-

sition below the roof; and means for supporting the front part from the roof when in use.

44. The combination with a car having bulk-heads, of a contracting upper berth comprising a panel of the length of the berth, 70 and an extension adapted to fold over the outer edge of the panel; and a mattress or bed bottom; the inner edge of the panel being pivoted or hinged to the bulk-heads and the berth when contracted and swung up occupying a substantially vertical position adjacent the wall and roof.

45. The combination with a car wall, of an apron or finishing strip secured to the roof; and a contracting upper berth comprising a 80 panel with a folding extension, said panel being hinged or pivoted to the car; the upper edge of the berth when contracted and swung up lying adjacent the said strip or apron.

46. The combination with a car wall, of a contracting upper berth comprising a rear panel portion with a curved extension which is pivoted to the car side, a movable front portion, and rope or chain supports for both the front and rear portions.

47. The combination with a car, of an upper berth comprising a panel of the length of the berth and of a width less than the width of the berth when arranged for use, said panel being pivoted at its inner edge adjacent to the car wall, and an extension adapted to occupy a position outside the outer edge of the panel and to be turned or shifted parallel with the panel, whereby when the panel is folded to a vertical position 100 the extension will occupy a position between the said panel and the car wall.

48. The combination with a car, of an upper berth comprising a panel of the length of the berth and of a width less than the width 105 of the berth when arranged for use, said panel being pivoted at its inner edge adjacent to the car wall, a folding or contracting mattress, and an extension adapted to occupy a position outside the outer edge of the panel 110 and to be turned or shifted over the outer edge of the panel, for the purpose set forth.

49. The combination with a car, of an upper berth comprising a panel having a curved inner edge said panel being of the length of the berth and of a width less than the width of the berth when arranged for use, the panel also being pivoted at its inner edge adjacent to the car wall, and an outer extension adapted to occupy a position outside the outer edge of the panel and to be turned or shifted to a position within the area of the panel, in substance as set forth.

50. The combination with a car of an upper berth comprising a panel curved at its inner edge, of the length of the berth, and of a width less than the width of the berth when arranged for use, said panel being pivoted at its inner edge adjacent to the car wall, and a hinged extension adapted to fold over the 130

edge of the said panel, whereby when the panel is turned up the extension will lie adjacent the car wall and out of sight.

51. The combination with a car, of an upper berth comprising a panel of less width than the berth pivoted at its inner edge adjacent the car wall, and an extension hinged to the end pieces of the panel and adapted to lie in a plane at the outer edge of the panel 10 and also to fold to a position within the area of the panel, the outer edge of said panel occupying a position adjacent the car roof when the same is turned up to a substantially vertical position.

15 52. The combination with a car, of an upper berth comprising a panel hinged at its inner edge adjacent to the car wall, and an extension hinged to the end pieces of the panel so it can be turned to occupy a position beyond the edge of the panel or occupy a position within the area of the panel, the outer edge of the panel when turned to a substantially vertical position being adjacent the roof of the car and the extension located between the car wall and said panel.

53. The combination with a car wall, of a pivoted upper berth, bulk heads between which the berth closes, fusees located upon the outer surfaces of the bulk heads, and 30 chains or cords connected to the fusees and the berth.

54. The combination with a car wall, of a pivoted upper berth, bulk heads each having an opening at the top, fusees secured outside 35 the bulk heads, friction wheels at the bulk head openings, and chains or cords passed over the friction wheels and secured at their opposite ends to the berth and fusees.

55. The combination with a car having 40 arch rails, and hooks in the arch rails, of an upper berth pivoted to the car side, supports secured to the outer edge of the berth and adapted to engage the hooks of the arch rails, and a guard for the upper berth suspended at 45 one edge by the hooks.

56. The combination with a car having a series of sections, folding upper berths, alcoves, and bulk head boards, of curtains or flexible blinds located at the roof within the 50 alcoves and adapted to be drawn down, for the purpose set forth.

57. The combination with two seat backs bounding an alcove, of a movable end partition, a removable cover, and means for supporting the cover below the top of the seat backs, whereby an inclosed receptacle is formed for bedding and a space above the cover between the seat backs is reserved for hand baggage, etc.

60 58. The combination with two seat backs at the sides of an alcove, of a movable end partition, a movable top cover located below the tops of the seat backs, and a wash basin located in the alcove and adjacent the car 65 wall.

59. The combination with a car having a series of sections and alcoves adjacent the opposite side walls thereof forming a central passage way, of rooms at the corners of the car and upon opposite sides thereof, one of said rooms at each end being longer than the other, and partitions or doors, as 57, located adjacent the ends of said longer rooms and extending across the central passage way.

60. The combination with a car having a series of sections and alcoves along opposite sides thereof forming a central passage way, of partitions 61 and partitions 57 in line with partitions 61 and extending across the central passage way, an alcove being located adjacent each partition 61, for the purpose set forth.

61. The combination in a sleeping car and with the wall, of three fixed seat backs or partitions in series located adjacent the wall and at right angles thereto dividing the floor area into a section 54 and an alcove space 37 adjacent the wall; seats with upholsterings movable to form a lower berth in the section; means for forming a horizontal upper berth above the seats and entirely within the section; and three head boards or partitions in connection with the seat backs, two of them being movable, for inclosing the section and alcove; said alcove space being open and unobstructed above the floor providing free standing room for the passenger in undressing and dressing, and said alcove also being shut off from the berths by a fixed seat back and movable partition so access to the same is possible only from the front of the section.

62. The combination in a sleeping car and with the wall, of three fixed seat backs or partitions in series located adjacent the wall and at right angles thereto dividing the floor area into a section 54 and an alcove space 37 adjacent the wall; seats with upholsterings movable to form a lower berth in the section; means for forming a horizontal upper berth above the seats and entirely within the section; and three head boards or partitions in connection with the seat backs, two of them being movable, for inclosing the section and alcove; said alcove space being open and unobstructed above the floor providing free standing room for the passenger in undressing and dressing, and said alcove also being shut off from the berths by a fixed seat back and movable partition so access to the same is possible only from the front of the section.

63. The combination in a sleeping car and with the wall, of a fixed partition and two fixed seat backs or partitions in series located adjacent the wall and at right angles thereto dividing the floor area into an alcove space 37 adjacent the wall and the fixed partition, and a section 54; seats with upholsterings movable to form a lower berth in the section; means for forming a horizontal upper berth above the seats and entirely within the sec-

105

130

tion; and two head boards or partitions in connection with the two seat backs, one of them being movable, to inclose the section; the said alcove space being open and unobstructed above the floor providing free standing room for the passenger in undressing and dressing, and said alcove also being shut off from the berths by a seat back and partition so access to the same is possible only from 10 the front of the section.

64. The combination in a sleeping car and with the wall, of a fixed partition and two fixed seat backs or partitions in series located adjacent the wall and at right angles thereto dividing the floor area into an alcove space 37 adjacent the wall and the fixed partition, and a section 54; seats with upholsterings movable to form a lower berth in the section; means for forming a horizontal upper 20 berth above the seats and entirely within the section; and two head boards or partitions in connection with the two seat backs, both of them being movable, to inclose the section; the said alcove space being open and unobstructed above the floor providing free standing room for the passenger in undressing and dressing, and said alcove also being shut off from the berth by a seat back and partition so access to the same is possible 25 only from the front of the section.

65. The combination in a sleeping car having a section adjacent the wall formed by the seat backs or partitions, of arch rails substantially in line with the seat backs; an upper berth having a rigid panel of the 35 length of the berth hinged with its inner edge at the wall and an outer portion foldable relative to the panel portion; bulk-heads; and means, as cords or chains, detachably 40 connecting the said outer foldable portion of the berth with the arch rails for supporting the said outer portion of the berth when in use.

66. The combination in a sleeping car 45 having a section and alcove adjacent the wall formed by the seat backs or partitions, of a folding upper berth in the section; and a

guard secured to part only of the outer edge of the upper berth when lowered and supported from the car roof; so an opening to 50 the berth is afforded only at the end.

67. The combination with a car, of a section bounded by seat backs and bulk-heads; alcoves adjacent the sections; a pivoted upper berth adapted to close to a substantially 55 vertical position between the bulk-heads; spring devices, as fusees, in the alcoves; ropes or chains connecting the berth and the spring devices; and bearings for said ropes or chains. 60

68. The combination in a sleeping car, of rigid seat backs located adjacent the wall and spaced apart to form an alcove and a section shut off from the alcove by the seat back, a wash basin at the wall in the alcove 65 between two seat backs, a permanent closet above the basin, and movable means to inclose part of the alcove space between the seat backs to form a receptacle. 70

69. The combination in a sleeping car, of rigid seat backs located at right angles to the car wall and spaced apart to form an alcove and a section; a folding wash basin at the wall in the alcove; and movable end and top partitions or boards to inclose a part of the 75 alcove space in front of the basin.

70. The combination in a sleeping car and with the floor and wall, of seat backs and partitions located adjacent the wall and substantially at right angles thereto dividing 80 the floor area into a section and an alcove space adjacent the wall; a folding wash basin and box located at the wall in the alcove space and substantially of the width of the alcove space to prevent water falling 85 upon the floor; and an openable pocket above the basin formed in part or wholly within the wall of the car whereby ample standing room is secured for the passenger within the alcove.
